DESIGN FOR AN UPRIGHT PIANO

William Zaiser, Rockville Centre, N. Y., assignor to Winter & Co., a corporation of New York

Application November 7, 1935, Serial No. 59,419

Term of patent 7 years

To all whom it may concern:

Be it known that I, William Zaiser, a citizen of the United States and a resident of Rockville Centre, in the county of Nassau and State of New York, have invented a new, original, and ornamental Design for Upright Pianos, of which the following is a specification, reference being had to the accompanying drawing, forming part thereof.

The drawing is a perspective view of an upright piano embodying my new design.

I claim:

The ornamental design for an upright piano substantially as shown.

WILLIAM ZAISER.
